UNITED STATES PATENT OFFICE.

HENRY J. KAST, OF WATERBURY, CONNECTICUT, ASSIGNOR TO AMERICAN PIN COMPANY, OF WATERBURY, CONNECTICUT, A CORPORATION OF CONNECTICUT.

FLOOR AND CEILING PLATE.

1,159,392.

Specification of Letters Patent.

Patented Nov. 9, 1915.

Application filed March 15, 1915. Serial No. 14,429.

To all whom it may concern:

Be it known that I, HENRY J. KAST, a citizen of the United States, residing in Waterbury, county of New Haven, and State of Connecticut, have invented certain new and useful Improvements in Floor and Ceiling Plates, of which the following is a full and clear specification.

This invention relates to floor and ceiling plates and has for its primary object to provide an improved construction, combination and arrangement of parts in a device of this character, which will enhance the ornamental appearance of such a device and better adapt it for use and to the requirements of shop practice involved in its manufacture.

One of the objects of the present invention is to provide improved means for movably connecting the main parts or segments 20 of which the floor and ceiling plate is constructed.

Another object is to provide improved means for latching those ends of the main parts or segments which are opened out to 25 adapt the floor and ceiling plate to be installed around a pipe.

Other and further objects will appear in the specification and be pointed out in the appended claims, reference being had to the 30 accompanying drawings which show the preferred embodiment of my invention.

In the drawings: Figure 1 is a top plan view of the floor and ceiling plate closed; Fig. 2 is a bottom plan view of the same; 35 Fig. 3 is a view similar to Fig. 2 with the segments opened out; Fig. 4 is a section on the line IV—IV, Fig. 3; Fig. 5 is a section on the line V—V, Fig. 3.

It has been a common expedient in the 40 art to construct floor and ceiling plates in two parts which may be entirely disconnected from each other and then assembled in position around a pipe. One of the main objections to such a construction was that 45 the parts being completely separable were frequently misplaced by becoming detached from their complementary parts. It has also been a common expedient to connect the parts or segments of a floor and ceiling 50 plate by a hinge, thus making the parts incapable of being disassociated, but such hinges have invariably formed a protuberance on the outer surface of the plate in use or have necessitated making such parts unsymmetrical and unlike each other. Both of 55 these expedients have proven not entirely satisfactory for these reasons. The present invention contemplates a construction which obviates the undesirable features of both, of the hereinbefore mentioned expedients while 60 at the same time providing several additional features of value.

Referring now to the drawings and more particularly to the particular embodiment of my invention shown therein, the floor and ceiling plate comprises two parts or segments 1 and 2 which are exact replicas of each other and hence adapted to be interchangeable in the course of manufacture.

As shown in Figs. 1, 2, 3 and 4, pipe-engaging lugs or fingers 3 are integrally formed with the segments 1 and 2, said fingers being commonly employed in the art for holding the floor and ceiling plate in the position to which it is adjusted. Referring 70 more particularly to Figs. 2 and 3, it will be noted that segments 1 and 2 are movable relatively to each other about an axis which approximately coincides with a point on the peripheral edge of the plate as a whole. 80 For the purpose of connecting these parts of segments 1 and 2 on one side and leaving them free to be opened out on the other side for adjustment into a desired position, suitable connecting means are employed which 85 makes it possible to swing said segments relatively to each other about an axis not within the contour of the plate itself. Preferably, this construction is made possible by embodying an arcuate slot or recess in one 90 segment and an arcuate slide or projection on the other segment. The requirements of manufacture are best observed in the present embodiment by securing to one of the segments a piece of sheet metal 4 having a 95 slot 5 formed therein concentric to the swinging axis. Slidable in the slot 5 is an arcuate protuberance 6 formed on a piece of sheet metal 7, said pieces 4 and 7 being secured to the inner walls of the segments 1 100 and 2 by autogenous welds 8. This mode of attachment has the advantage of obviating the use of rivets which would mar the ornamental appearance of the exposed surface of the segments 1 and 2 and thus impair its 105 ornamental appearance. At the same time this construction obviates the use of an ordinary hinge which necessitates the segments 1 and 2 being constructed unsymmetrically and hence requires a separate die for each 110 segment which is not the case with the present invention.

- In order to retain the lug 6 within the slot 5, a flange 9 is secured to the lug 6 and overlaps the edges of said slot. Said slot is preferably formed in a raised arcuate portion 10 of the sheet metal piece 4 to adapt it to slide over a protuberant portion of the sheet metal piece 7 which carries the lug 6. A resilient lug 11 is provided on the sheet metal piece 7 in suitable position to frictionally engage the portion 10 of the sheet metal piece 4 when the segments 1 and 2 are brought together as shown best in Fig. 2, the lug 11 exerting a tendency to retain the segments in closed position. Secured to the inner wall of the segment 1, by means of autogenous welds 12, is a sheet metal piece 13, which is provided with an opening 14 and an inwardly turned flange 15 which acts as a keeper for a lug 16 mounted on a resilient tongue 17 which forms part of a sheet metal piece 18 secured by autogenous welds 19 to the inner wall of the segment 2. The resilient tongue 17 is displaced inwardly somewhat with respect to the piece 18 to adapt it to force the lug 16 behind the flange 15 when the segments are brought together. A cam finger 20 is integrally formed with the piece 18 by cutting the tongue 17 from said piece as indicated in Figs. 2 and 3, said cam 20 being adapted to engage the inner wall of the segment 1 as the two segments are brought together in such a way as to insure the outer surfaces of said segments being brought into positive alinement. As shown in Fig. 2, the cam 20 with the resilient tongue 17 substantially fills the opening 14 when the segments are in closed position. As indicated in Fig. 5, the flange 9 has a depressed center 21 which fits a similar depression 22 in the arcuate lug 6 carried by the sheet metal piece 7.
- The advantages of my improved construction will now be readily understood and briefly are as follows. Each of the segments 1 and 2 is susceptible of being stamped in one and the same die. They are provided with permanent connecting means and latching means without marring the external surface and thereby impairing the ornamental appearance of the same. The permanent connecting means which permits relative movement without disassociation, are adapted to permit a movement about an axis distant from themselves thus rendering the provision of an ordinary hinge unnecessary which would make it practically impossible to construct the segments as exact replicas of each other without forming protuberances on their outer peripheries. As a matter of fact, a slight play between the sides of slot 5 and the arcuate walls of lug 6 may shift the swinging axis entirely outside of the peripheral edge of the segments 1 and 2. Moreover

both the permanent connecting means and the releasable latching means are adapted to act as lugs after the floor and ceiling plate has been installed. Also the finger cam 20 as well as the connecting pieces 4 and 7, serve to hold the outer surfaces of the segments 1 and 2 in perfect alinement, thus materially aiding their ornamental appearance.

What I claim is:—

1. A floor and ceiling plate comprising segments, said segments being respectively provided with interengaging connecting members, one of said connecting members having a portion secured to the inner face of one of said segments and another portion spaced therefrom to form a recess, and the other of said connecting members having a portion secured to the inner face of the other segment and another portion projecting beyond said other segment and suitably disposed to enter said recess, said connecting members being provided with means permanently and movably connecting them.

2. A floor and ceiling plate comprising segments movable relatively to each other about an axis one of said segments being provided with a piece having an arcuate slot or recess concentric with a predetermined swinging axis, and the other segment being provided with an arcuate lug concentric with said axis and moving in said slot.

3. A floor and ceiling plate comprising segments movable relatively to each other about an axis one of said segments being provided with a piece having an arcuate slot or recess concentric with a predetermined swinging axis, and the other segment being provided with an arcuate lug concentric with said axis and moving in said slot, said pieces being integrally formed with the inner walls of said segments.

4. A floor and ceiling plate comprising segments movable relatively to each other about an axis one of said segments being provided with a piece having an arcuate slot or recess concentric with a predetermined swinging axis, and the other segment being provided with an arcuate lug concentric with said axis and moving in said slot, said pieces being integrally formed with the inner walls of said segments, said pieces being provided with slidably overlapping portions and one of said pieces being provided with a spring lug suitably disposed to resiliently clamp the overlapping portion of the other piece adjacent the end of the closing movements of said segments.

HENRY J. KAST.
